G. F. KRIEGER

CRANK PIN TOOL

Filed Aug. 18, 1922

INVENTOR.
George F. Krieger

BY

Geo. F. Kimmel

ATTORNEY.

UNITED STATES PATENT OFFICE.

GEORGE F. KRIEGER, OF WISCONSIN RAPIDS, WISCONSIN.

CRANK-PIN TOOL.

Application filed August 18, 1922. Serial No. 582,776.

To all whom it may concern:

Be it known that I, GEORGE F. KRIEGER, a citizen of the United States, residing at Wisconsin Rapids, in the county of Wood 5 and State of Wisconsin, have invented certain new and useful Improvements in Crank-Pin Tools, of which the following is a specification.

This invention relates to crank pin tools, 10 and has for its object to provide a tool of such class, in a manner as hereinafter set forth, with means especially adaptable for the accurate finishing or rounding of the crank pins of internal combustion engine 15 shafts, particularly those of motor vehicle engines, and further for refinishing scored and worn crank pins of the crank shafts thereof, and, in the latter instance, in a manner not requiring the removal of the 20 crank shaft from its operative position in the engine assembly.

A further object of the invention is to provide a tool, of such class, in a manner as hereinafter set forth, with means for 25 automatically centering a crank pin within the jaws of the tool simultaneously with the adjustment of the cutter-carrying head block to operative position.

Further objects of the invention are to 30 provide a tool of such class, which is simple in its construction and arrangement, adjustable, strong, durable, compact, efficient and convenient in its use, readily set up in operative position, and comparatively inexpensive.

With the foregoing and other objects in view, the invention resides in the novel construction, combination and arrangement of parts, as hereinafter more specifically described, and illustrated in the accompanying drawings, wherein is shown an embodiment of the invention, but it is to be understood that changes, variations and modifications can be resorted to, which come within 45 the scope of the claims hereunto appended.

In the drawings, wherein like reference characters denote corresponding parts throughout the several views:—

Figure 1 is a front elevation of a crank 50 pin tool in accordance with this invention,

Fig. 2 is a side elevation thereof,

Fig. 3 is a sectional elevation partly broken away,

Fig. 4 is a section on the line 4—4 of Fig. 2,

55 Fig. 5 is a section on the line 5—5 of Fig. 2,

Fig. 6 is a top plan view of the stationary jaw.

Referring to the drawings in detail, the tool includes a handle member 10, which terminates in a threaded shank 11, the latter merging into the stem 12, of the fixed jaw of the tool, to be hereinafter referred to. 60

The stem 12 is square in cross section, and the shank 11 cylindrical, as well as being peripherally threaded. Mounted on the shank 11, is an adjusting nut 13, which is employed for adjusting the position of the movable jaw of the tool, to be hereinafter referred to. 65

The stationary jaw of the tool, includes 70 the stem 12, which is somewhat elongated, and which merges at its outer end in a forwardly projecting curved jaw body, and which is bifurcated. The forwardly projecting curved jaw body, is indicated at 14, 75

and the furcation, due to the bifurcation of the jaw body 14, is indicated by the reference character 15. The inner face of the curved jaw body 14, in proximity to the forward end thereof, is provided with a dovetail groove 16, in which is seated, a transversely extending triangular-shaped abutment member 17, which is of a length greater than the width of the jaw body 14, 80 so as to project from each side of the said jaw body 14. The abutment member 17 extends across the furcation 15, and mounted in the latter, as well as arranged forwardly of the element 17, and further projecting inwardly of the jaw body with respect to the inner side of the element 17, is a lubricating element 18, which is formed of an absorbent fabric and is saturated with a lubricant. A pin 19 extends through the jaw body 14, at 85 the forward end thereof, for the purpose of detachably securing the lubricating element or member 18, in position. The member 18 projects inwardly from the jaw body 14, so as to come in contact with the work operated on. 90

The adjustable jaw, which is slidably mounted on the stem 12 of the stationary jaw, and which is further adjusted by the nut 13, carried by the shank 11, includes an elongated squared sleeve 20, which has its inner end formed integral with an annular collar 21, which abuts against the nut 13, so that when the latter is adjusted lengthwise of the shank 11, the sleeve 20 can be moved correspondingly. The forward end 100 105 110

of the sleeve 20 terminates in a jaw body coupling member, which is formed with a squared bore 22, and is mounted on the stem 12. The coupling member is indicated at 23, and is of greater thickness than the thickness of the body of the sleeve 20. The member 22 has a port 24, for the purpose of supplying a lubricant to the interior thereof, so that the member 23, as well as the sleeve 20, will freely slide on the stem 12, of the stationary jaw. Projecting forwardly from the member 23, as well as formed integral therewith, is a neck portion 25, which carries the adjustable jaw body 26. The member 23, neck 25, and jaw body 26, has that portion opposing the jaw body 14, cut away to provide a V-shaped jaw, and the working faces of the latter are indicated at 27, 28.

At the point of jointure, between the working faces 27, 28, of the adjustable jaw, the jaw body 26 is formed with a transversely extending pocket 29, for the reception of a cutter 30. The jaw body 26 below the pocket 29, centrally thereof, is formed with a socket 31, having the wall thereof threaded. The socket 31 extends parallel with respect to the stem 12 of the stationary jaw. Disposed at right angles with respect to the pocket 29, is a bore 32, which extends through the rear of the jaw body 26, neck 25, and the forward portion of the member 23, and said bore is in alignment with the port 24. Mounted in the bore 32, is a cylindrical clamping element 33, which abuts against the cutter 30 and clamps the same against the forward wall of the pocket 29. The clamping element or member 33 is secured in clamping position through the medium of a threaded retaining member 34, the latter being disposed at right angles with respect to the member or element 33 and abuts against the rear end of the said member 33. The retaining member 34 has threaded engagement with a pocket 35, which is disposed at right angles with respect to the bore 32. The pocket 35 is formed in the neck 25, and which terminates at its outer end in a recess 36, at one side of the neck 25 and which is of a size to receive an operating element 37, for the retaining or securing element or member 34. The rear end of the member or element 33 is tapered as at 38, and which is engaged by the tapered inner end 39 of the element 34, and by this arrangement, when the element 34 is screwed inwardly, the pointed inner end 39 bearing against the pointed inner end 38 of the element 33, will force the element 33 forwardly, thereby clamping the cutter 30 against the forward wall of the pocket 29. The clamping of the cutter 30 in the position just referred to, is had subsequent to the adjusting of the cutter 30, to the position desired for operation upon the work.

The cutter or scraper 30, has its inner edge abutting against a pair of adjusting screws 40, 41, which are threaded as at 39, and the said screws 40, 41, are mounted in lateral flanges 42, which extend from a yoke-shaped member 43. Seated on the head 46, of an adjusting screw 44, which adjustably engages with the threads of the wall of the socket 31, is the base of the member 43. The base of the member 43, is indicated at 45, and which is provided with an opening 45', for the passage of the screw 44. The flanges 42 are apertured and the walls are threaded so that engagement of the screws 40, 41, with the flanges 42, will be had. The slits 49 are provided for the purpose of adjusting the screws 40, 41, when occasion requires. Interposed between the jaw body 26, and the base 45, of the member 43, as well as surrounding the screw 44, is a coiled spring 50, which is employed for imparting tension, not only to the member 43, but to the adjusting screw 44, so that during the operation of the adjusting of the screw 44, or the member 43, such action will be had against the tension of the spring 50. The head 46 is tapered, and provided with a micrometer scale 47, and further provided with squared portions 48, for engagement by a tool for the purpose of adjusting the head 46, when occasion so requires. The scraper or cutter 30, can be adjusted independently of the member 43, or the screw 44, by the adjusting of the screws 40, 41.

The working face 28 of the V-shaped jaw of the adjustable jaw body, is provided with a pocket 51, in which is mounted an absorbent or lubricant element 52, which consists of a body of absorbent material, saturated with a suitable lubricant, and said element 52 is secured to the jaw body, through the medium of a wire 53, passing through an opening 54, in the jaw body 26, and bent at its outer end, so as to abut against the jaw body 26, under such conditions retaining the element 52 in the socket or recess 51.

The V-shaped jaw of the adjustable jaw body 26, provides for centering the work, when it is desired to be operated on and said V-shaped jaw, in connection with the abutment 17, when the adjustable jaw has been shifted to its desired point of adjustment, will securely hold the work during the operation thereon, of the cutter or scraper 30.

By providing the elements 35, 37, and 33, the cutter or scraper 30, can be securely clamped in position, after being adjusted for operative engagement with the work supported by the V-shaped jaw of the adjustable jaw body 26.

After clamping the work in position, and adjusting the cutter, or scraper 30, the tool is revolved around the work, and the cutter 30, acting on the face of the work will finish or round the work in the manner desired,

and during the operation or rather revolving the tool, the necessary amount of lubricant will be supplied so as to set up a satisfactory working.

5 From the foregoing description, taken in connection with the arrangement of elements and illustrated by the drawings, it will be readily apparent that a crank pin tool is set up, which provides for the accurate finishing or rounding of the crank pins of engine shafts, as well as a tool for refinishing scored and worn crank pins, and although the description and drawings set forth the preferred embodiment of the tool, 10 yet it is to be understood that the specific terms and details of construction, arrangement and operation and various changes in and modifications of the same can be resorted to without departing from the spirit of 15 the invention:

What I claim is:—

1. A tool for the purpose set forth comprising an adjustable jaw body provided with a V-shaped jaw, an adjustable cutter 25 positioned at the point of jointure between the working faces of said V-shaped jaw, means arranged exteriorly of said jaw body for adjusting said cutter, means arranged within said jaw body for clamping 30 said cutter in adjusted position, and a lubricating element mounted in one of the working faces of said V-shaped jaw and means carried by said jaw body for securing said lubricating element thereto.

35 2. A tool for the purpose set forth comprising an adjustable jaw body provided with a V-shaped jaw, a cutter mounted in the jaw body and projecting between the working faces of said jaw, adjustable supporting means exteriorly of the jaw body for adjusting said cutter, and means adjustably connected with the jaw body and connected with said adjustable supporting means for adjusting the cutter independent 40 of the adjusting of the said adjustable supporting means.

45 3. A tool for the purpose set forth comprising an adjustable jaw body provided with a V-shaped jaw, a cutter mounted in the jaw body and projecting between the working faces of said jaw, adjustable supporting means exteriorly of the jaw body for adjusting said cutter, means adjustably connected with the jaw body and connected with said adjustable supporting means for adjusting the cutter independent of the adjusting of the said adjustable supporting means, and releasable means mounted in said jaw body for clamping said cutter in position.

50 4. A tool for the purpose set forth comprising an adjustable jaw body provided with a V-shaped jaw, a cutter mounted in the jaw body and projecting between the working faces of said jaw, adjustable sup-

porting means exteriorly of the jaw body for adjusting said cutter, means adjustably connected with the jaw body and connected with said adjustable supporting means for adjusting the cutter independent of the adjusting of the said adjustable supporting means, releasable means mounted in said jaw body for clamping said cutter in position, and a lubricating element mounted in one of the working faces of said V-shaped jaw and connected with said jaw body.

5. A tool for the purpose set forth comprising a stationary jaw, a lubricating element carried by said jaw and projecting inwardly therefrom, an adjustable jaw body 80 provided with a V-shaped jaw, and a lubricating element mounted in said V-shaped jaw and connected with said adjustable jaw body.

6. A tool for the purpose set forth comprising a stationary jaw, a lubricating element carried by said jaw and projecting inwardly therefrom, an adjustable jaw body provided with a V-shaped jaw, a lubricating element mounted in said V-shaped jaw and 90 connected with said adjustable jaw body, and an adjustable cutter mounted in said jaw body and extending between the working faces of said V-shaped jaw.

7. A tool for the purpose set forth comprising a stationary jaw, a lubricating element carried by said jaw and projecting inwardly therefrom, an adjustable jaw body provided with a V-shaped jaw, a lubricating element mounted in said V-shaped jaw and 95 connected with said adjustable jaw body, an adjustable cutter mounted in said jaw body and extending between the working faces of said V-shaped jaw, and means mounted in said jaw body for clamping said 100 cutter in adjusted position.

8. A tool for the purpose set forth comprising a stationary jaw, an adjustable V-shaped jaw, a cutter projecting between the working faces of said V-shaped jaw, means 110 for clamping said cutter in adjusted position, and means adjustably connected with the V-shaped jaw and engaging said cutter exteriorly of the jaw for adjusting the cutter.

9. A tool for the purpose set forth comprising a stationary jaw provided on its inner face with a transversely extending V-shaped abutment, an adjustable jaw body provided with a V-shaped jaw opposing said abutment, an adjustable cutter mounted in 120 said adjustable jaw body and extending between the working faces of said V-shaped jaw, releasable means mounted in said jaw body for clamping said cutter in adjusted position, and means adjustably connected with said jaw body and engaging said cutter, exteriorly of the jaw body, for adjusting and supporting said cutter.

10. A tool for the purpose set forth comprising a stationary jaw provided on its in-

- ner face with a transversely extending V-shaped abutment, an adjustable jaw body provided with a V-shaped jaw opposing said abutment, an adjustable cutter mounted in said adjustable jaw body and extending between the working faces of said V-shaped jaw, releasable means mounted in said jaw body for clamping said cutter in adjusted position, means adjustably connected with 10 said jaw body and engaging said cutter, exteriorly of the jaw body, for adjusting and supporting said cutter, and a lubricating element carried by said fixed jaw and adjustable jaw body.
11. A tool for the purpose set forth comprising a stationary jaw provided on its inner face with a transversely extending V-

shaped abutment, an adjustable jaw body provided with a V-shaped jaw opposing said abutment, an adjustable cutter mounted in 20 said adjustable jaw body and extending between the working faces of said V-shaped jaw, releasable means mounted in said jaw body for clamping said cutter in adjusted position, means adjustably connected with 25 said jaw body and engaging said cutter, exteriorly of the jaw body, for adjusting and supporting said cutter, and means for imparting tension to the said adjusting and supporting means for said cutter.

In testimony whereof, I affix my signature hereto.

GEORGE F. KRIEGER.
